WRINGER-MOP APPARATUS

William M. Christopher, Tonawanda, N. Y.

Application January 30, 1937, Serial No. 123,289

2 Claims. (Cl. 15—119)

The invention relates to a wringer-mop apparatus.

The object of the invention is to provide, in a manner as hereinafter set forth, an apparatus of the class referred to, including a wringer element which not only functions for wringing the mop, but further functions to constitute a holder for the mop when the latter is used for mopping a surface.

10 A further object of the invention is to provide, in a manner as hereinafter set forth, an apparatus of the class referred to functioning as a combined portable mop and wringer and with the apparatus including as elements thereof a combined mop wringer and holder device, a carrier for the latter, a handle for the carrier, and operating means for the device supported from the carrier and handle and actuated from a point intermediate the ends of the latter.

20 Further objects of the invention are to provide, in a manner as hereinafter set forth, a wringer-mop apparatus which is comparatively simple in its construction and arrangement, strong, durable, light in weight, compact, conveniently used for mopping purposes, expeditiously operated to provide for a wringing action on the mop, thoroughly efficient in its use, readily assembled and comparatively inexpensive to manufacture.

With the foregoing and other objects in view, 30 the invention consists of the novel construction, combination and arrangement of parts as will be more specifically referred to and are as illustrated in the accompanying drawings wherein is shown an embodiment of the invention, but it is 35 to be understood that changes, variations and modifications may be resorted to which fall within the scope of the invention as claimed.

In the drawings:

Figure 1 is a fragmentary view in front elevation of the apparatus with the mop and combined guiding and supporting element omitted.

Figure 2 is a perspective view of the apparatus with the handle thereof broken away showing the position of the mop after the wringing operation has been applied thereto.

Figure 3 is a fragmentary view in vertical section illustrating one position of the mop during the wringing thereof.

Figure 4 is a fragmentary view in vertical section upon an enlarged scale.

Figure 5 is a detail in elevation illustrating the manner in which the carrier is anchored to the handle.

Figure 6 is a section on line 6—6, Figure 4.

Figure 7 is a fragmentary view in elevation of a part of the carrier.

Figure 8 is a section on line 8—8, Figure 4, and

Figure 9 is a fragmentary view in vertical section of the wringer element.

A wringer mop apparatus in accordance with

this invention includes a spring controlled combined holder and wringer mechanism 16 for a mop 15 of the endless type, a carrier 17 for mechanism 16, a handle 18 for the carrier 17, and a manually actuated operating means 19 for the mechanism 16. There is shown a form of a combined mop guiding and carrier supporting element 20 which may be used in connection with a water container when wringing the mop as illustrated in Figures 2 and 3.

The spring controlled combined mop holding and wringing mechanism 16 has the mop 15 permanently connected thereto. When a mopping action is carried out the mop 15 is arranged in outwardly extended relation with respect to the mechanism 16. The latter includes a revolvable outer wringer or holder roller 28. The mounting for roller 28 is to be referred to, a revolvable bodily shiftable inner wringer roll 29, and an adjustable resilient compression structure 30 for roll 29. The rolls 28, 29 are formed of any suitable material and are of any suitable diameter and length. Preferably, the rolls are of the same diameter. The mop 15 is connected to and encompasses the roll 28. A portion of the length 25 of the body of mop 15 is arranged between the said rolls. Roll 28 is formed with an axial bore 31 and capped, as at 32, at each end thereof. A fixed shaft 33 extends through bore 31 and is of greater length than the length of roll 28. The 30 periphery of the latter is smooth throughout. The roll 29 is formed with a pair of oppositely disposed axial sockets 34, 35 opening at the opposite ends thereof. The socket 34 is of polygonal cross section. The socket 35 is of cylindrical cross section. The periphery of the roll 29 is formed throughout with spaced cavities 36. The roll 29 is capped at each end as at 37. The caps at the ends of the rolls 28, 29 are axially apertured. Secured in the socket 34 and extending outwardly therefrom is a short shaft or pintle 38 of 40 polygonal cross section. Secured in the socket 35 and extending outwardly therefrom is a stub shaft or pintle 39 of circular cross section. The rolls 28, 29 are arranged in superimposed relation. The roll 29 is permanently under compression and is bodily adjusted towards and from the roll 28 to provide a space of the desired width for the passage of a stretch of the mop 15 and in this connection attention is directed to Figures 50 2 and 3. When the mop 15 is to be used for mopping, the rolls 28, 29 are arranged in a manner whereby a stretch of the mop will be disposed therebetween and the pressure on roll 29 will be such that roll 29 will coact with the roll 28 for 55 clamping such stretch to the rolls for the purpose of disposing mop 15 in outwardly extended relation with respect to the mechanism 16. The clamping function of roll 29 is transmitted from the structure 30. The cavities 36 function to 60

assist in the clamping of the mop to mechanism 16, due to the fact that spaced portions of the body part of the mop will be forced into several of the cavities when the mop is clamped to mechanism 16. When the mop is to be subjected to a wringing action, the pressure on roll 29 is relieved to the desired extent to permit of a stretch of the body part of the mop being successively compressed for expelling the water to the desired extent and for said stretch to be moved inwardly or outwardly with respect to the rolls.

15 or outwardly with respect to the carrier 17. The compression structure 30 of the mechanism 16 includes a pair of vertically adjustable spaced parallel slides 41, 42 which are slidably arranged on the outer faces of the lower portions 43, 44 respectively of the sides 45, 46 respectively of the carrier 17. The lower portions of the sides of the carrier 17 are slotted as at 47 and such slots extend from a point removed from the lower ends 20 of said lower portions to above the upper ends of the latter. The slides 41, 42 extend across the slots 47 in the side portions 43, 44, as well as extending slightly below the bottom of said slots. The slide 41 is formed with an opening 48 and an opening 49 below and aligning with the opening 48. Integral with the inner face of slide 41 and registering with the openings 48, 49 are inwardly extending flanged bearings 48^a, 49^a respectively which pass through the slot 47 of and slidably 25 connect the slide 41 to carrier side 45. The ends 30 of the roll 29 and the caps 37 on such ends are countersunk. The countersink at one end of roll 29 has mounted therein the bearing 49^a. The ends of the slides 41

29 has modified . . . . .
Positioned against the outer face of the slide 41,
35 as well as being suitably secured to slide 41 for the
purpose of bodily moving with the latter is a cas-
ing 50 having arranged in the upper portion
thereof a gear wheel 51 which meshes with and
drives a gear 52 arranged in the lower portion of
40 the casing. The gear wheel 51 has a hub 53
which extends outwardly and inwardly with re-
spect to casing 50. The gear wheel 52 is provided
with a hub 54 which extends outwardly and in-
wardly with respect to casing 50. A flange bear-
45 ing 55 is provided on the inner end of hub 53 and
which abuts the inner end of bearing 48a. The
inner part of hub 53 extends through the bearing
48a. The hub 53 is fixedly secured to a polygonal-
shaped driven shaft 56 for operating gear 51.
50 The shaft 56 extends inwardly from slide 41. The
hub 54 of gear wheel 52 is fixedly secured to the
shaft 38. Flanged bearings 56a are used for the
outer portions of the hubs 53, 54.

outer portions of the carrier.

The structure 30 includes a resilient pressure applying or spring member 51 of skeleton form provided with reduced ends 58, 59. A means to prevent the spreading of the reduced end 58 is indicated at 60 and a means to prevent the spreading of the reduced end 59 is indicated at 61.

60 The reduced ends 58, 59 of the member 51 extend through the upper ends of the slots in the lower portions 43, 44 of the sides 45, 46 of the carrier 11. The reduced ends 58, 59 of the member 51 bear respectively on the upper ends of the slides 41, 42, 65 for applying pressure thereto whereby the slides will be shifted to an extent to provide for roll 29 clamping the body part of mop 15 against roll 28.

The structure 30 includes a compression controlling means for member 57 consisting of an 70 upstanding rod 62 having a threaded lower portion 63. The rod 62 extends through the member 57 and carries a sleeve-like adjustable nut 64 which engages with the threads 63 and is employed for increasing and decreasing the tension 75 of member 57. The nut 64 extends through the

member 51 and is formed in proximity to its lower end with an annular peripheral groove 65 in which is seated member 51 whereby the latter is connected to rod 62 above the lower end of the nut. The adjusting of the nut 64 towards the lower end of rod 62 increases the tension of member 51 and an increase of pressure against the upper ends of slides 41, 42 which in turn will transmit such pressure to roll 29 to tightly clamp mop 15 to mechanism 16. The upper end of the rod 62 is offset as at 66 to provide a clearance for a transmission shaft, to be referred to, of the operating means for the mechanism 16. The offset portion 66 of the rod 62 has its upper part 67 extended into the handle 18 and also into the body of the latter as at 68. The part 67 is anchored to handle 18 as at 69. The member 51 is of arcuate contour. The slide 42 is formed with an opening 70 and extending through and integral with the wall of opening 70 is a flanged bearing 71 which passes through the slot 47 in side portion 44 and slidably connects slide 42 to carrier side 46. The shaft 39 revolves in bearing 71 and is bodily carried therewith when the slide 42 shifts in opposite directions simultaneously when the slide 41 is shifted in like directions. The bearing 71 extends into the countersink at the other end of roll 29.

into the countersink at the other end of the 1. The lower portion 43 of the side 45 of the carrier 17 is formed with a key-hole shaped opening 72 for receiving the reduced portion 73 of the shaft 33 for the purpose of removably connecting the end 73^a of shaft 33 to one side of the carrier 17. The lower side portion 44 of carrier 17 has an opening 74 and an inwardly extending tubular bearing 75 registering with the opening 74. The shaft 33 extends through bearing 75 and the lower side portion 44. The shaft 33 at its other end is enlarged as at 76 to provide a head abutting the outer face of portion 44 of the carrier 17. The head 76, in connection with the reduced portion 13 and opening 72 act to detachably connect shaft 33 to the carrier 17. The bearing extends into axial bore 31 of roll 28. The cap at the other end of roll 28 is formed with an inwardly extending tubular bearing 78 which registers with the axial opening thereof and extends into the axial bore 31 of roll 28. The bearing 78 is arranged in endwise alignment with the bearing 75. The shaft 33 extends through the bearings 75, 78. The roll 28 revolves about shaft 33 and bearing 78. The shaft 33 further functions as a means for connecting the side portions 43, 44 of the carrier together to prevent the spreading of such portions. The side portions 43, 44 of like form

The carrier 17 has its sides 45, 46 of like form, but oppositely disposed and said sides not only include the outer portions 43, 44 but also inner portions 79, 80 as well as intermediate portions 81, 82 extending towards each other at an inclination from their lower to their upper ends whereby the upper portions 79, 80 will be inset with respect to the lower portions 43, 44. The upper portions 79, 80 are secured against opposite sides of the lower end of handle 18 by the holdfast means 83. The lower ends of the lower portions 43, 44 are provided with inwardly extending flanges 84. The portions 43, 44, 81, 82 in cross section are of inwardly opening channel-shaped contour. The portions 79, 80 in cross section are of segmental contour. The handle 18 has a solid section 85 and

The handle 18 includes a solid section 85 and a tubular section 86. The lower end terminal portion 87 of section 85 is reduced and extends into and frictionally engages with the inner face of the outer end of section 86. The latter in proximity to section 85 is formed with a pair

of diametrically opposed openings 88, 89. The opening 88 is of greater diameter than the opening 89. Encompassing and secured to the section 86 is an annulus 90 which is enlarged at one side as at 91. The annulus 90 is formed with a pair of diametrically opposed openings 92, 93. The opening 92 is of greater diameter than the opening 93 but of less diameter than the opening 88. The opening 92 registers with the opening 88. The opening 93 is of the same diameter as the opening 89 and registers therewith.

The manually actuatable operating means 19 for the mechanism 16 is employed for revolving the roll 29 which in turn will provide for the 15 revolving of the roll 28. The means 19 includes an operating shaft 94 disposed lengthwise of the section 86 of the handle 18. Within the section 86 is arranged an inverted cup-shaped upper bearing 95 for and having an axial opening 96 20 through which passes shaft 94. Arranged within the section 86 is an inverted lower cup-shaped bearing 97 for and having an axial opening through which passes shaft 94. The latter extends upwardly from bearing 95 and has fixed to 25 its upper end a beveled pinion 99 meshing with a beveled gear 100 fixed to the reduced portion of a shaft 102 disposed in transverse relation with respect to section 86, mounted in one end in the openings 89, 93 revolvably connected at such end 30 to annulus 90 and having its other end 103 reduced and peripherally threaded. The gear 100 has a part thereof arranged in opening 88. The hub of gear 100 is mounted in and extends outwardly from opening 91. The outer end of the 35 hub of gear 100 is reduced. Positioned on the reduced portion of the hub of gear 100 and bearing against the remaining portion of the hub is a crank 104 provided with a handle means 105. The crank 104 is clamped on the hub of the gear 40 100 by a clamping nut 106 secured to the end portion 103 of shaft 102. On the revolving of the crank 104 shaft 102 will be carried therewith, as well as the gear 100 whereby the latter meshing with the pinion 99 will provide for the operation 45 of shaft 94. The bearing 97 is cut away as at 107 (Figure 6) to provide a clearance for the part 67 of the offset upper portion 66 of the rod 62. The lower end of shaft 94 has fixed thereto a 50 stop collar 108 which coacts with the lower bearing 97 to arrest the upper shift of shaft 94. The downward shift of shaft 94 is arrested by the hub of pinion 99 engaging with the top of the upper bearing 95.

The operating means 19 includes a transmission shaft 109 formed of a pair of telescopic sections 110, 111 and with the section 110 slidably arranged in and extended from the lower end of section 111. The shaft 109 is disposed at an outward inclination with respect to the lower end of the shaft 94. The section 110 is universally connected at its lower end, as indicated at 112 to the inner end of the shaft 56. The section 111 of the shaft 109 is universally connected at its upper end with the lower end of the shaft 94 as indicated at 113. When the combined guiding and supporting element 20 is employed it is mounted upon spaced portions of the top edge 114 of bucket 115 during the wringing operation and it not only functions to guide stretches of the mop 15 but further acts as a support for the carrier 17.

When the shaft 94 is operated, on the revolving of the crank 104, the transmission shaft 109 will be revolved from shaft 94, and shaft 109 will

transmit a revolving movement to the shaft 56 which in turn will revolve the gear 51, provide for the operation of gear 52 and the revolving of roll 29 and which in turn will provide for the revolving of the roll 28. The operation of the rolls 28, 29 is had when the apparatus is used for wringing out the mop. Owing to the manner in which the operating means 19 is set up relative to the shaft 56 the roll 29 may be operated in a clockwise or an anticlockwise direction.

By pressing upwardly the roll 28 at a point in proximity to carrier side portion 43 shaft 33 may be disconnected from the carrier and carry roll 28 therewith for the purpose of removing or connecting the mop from and to said roll.

Although the mop is shown as embodying a pair of ties for the mop body, yet it is to be understood that the number of ties may be increased as desired.

In operating the mop it is first rinsed in a pail 20 or bucket and the carrier is then placed on the carrier support and mop guide in a manner whereby the major portion of the mop will be positioned in the pail or bucket. A wringing action is then applied to the mop and the latter 25 will be caused to assume the position shown in Figure 2, that is, exteriorly of the bucket or pail.

What I claim is:

1. In a wringer-mop apparatus of that type including a carrier, a pair of lengthwise aligned 30 revoluble rolls within the carrier and a handle secured to the carrier, the combination of a pair of slides positioned at the sides of the carrier, means for revolvably supporting one of said rolls, means for revolvably supporting one end of 35 the other of said rolls from one of said slides, a gear mechanism carried by the other of said slides and connected to the other end of said other roll for revolving it, a shaft connected to said gear mechanism for driving it, a transmission shaft universally connected at one end to the said other shaft, and operating means for said transmission shaft universally connected to the other end of the latter, said operating means being arranged within and extended from the 40 handle for manual actuation.

2. In a wringer-mop apparatus of that type including a carrier, a pair of lengthwise aligned rolls within the carrier and a handle secured to the carrier, the combination of a pair of slides 50 positioned at the sides of the carrier, means for revolvably supporting one of said rolls, means for revolvably supporting one end of the other of said rolls from one end of said slides, a gear mechanism carried by the other of said slides and connected to the other end of said other roll for revolving it, a shaft connected to said gear mechanism for driving it, a transmission shaft universally connected at one end to the said other shaft, an operating means for said transmission 60 shaft universally connected to the other end of the latter, said operating means being arranged within and extended from the handle for manual actuation, a resilient compression element arranged within the carrier and having an end 65 terminal portion bearing on said slides, a tubular internally threaded adjuster for and turnably attached to the compression element, and an upstanding stationary part extending into and having threaded engagement with the adjuster, 70 said part being connected at its upper end to said handle.

WILLIAM M. CHRISTOPHER.
